United States Patent Office

Des. 190,583
Patented June 13, 1961

190,583

SCREW-ON CONNECTOR

William G. Schinske, Sycamore, Ill., assignor to Ideal Industries, Inc., Sycamore, Ill., a corporation of Delaware

Filed July 12, 1960, Ser. No. 61,322

Term of patent 14 years

(Cl. D26—1)

FIG. 1.

FIG. 2.

FIG. 3.

I claim:

The ornamental design for a screw-on connector, as shown.
